UNITED STATES PATENT OFFICE

WALTER L. CHURCH, OF HOUSTON, TEXAS, ASSIGNOR OF ONE-HALF TO W. L. PEARCE,
OF HARRIS COUNTY, TEXAS

PIPE CUTTER

Application filed April 29, 1929. Serial No. 359,093.

This invention relates to new and useful improvements in a pipe cutter.

One object of the invention is to provide an implement of the character described which may be let down into a pipe stuck in a well bore, and through which said stuck pipe may be cut into sections for removal, a section at a time.

Another object of the invention is to provide a pipe cutter operable through a tubular stem from the ground surface with provision for permitting the drilling fluid in the well to flow into and fill said stem as the device is being lowered to the end that said stem will not be collapsed by the pressure of said fluid; provision also being made for permitting said fluid to drain out of the stem back into the bore when the cutter is being withdrawn from the bore.

A further feature of the invention resides in the provision of a pipe cutter having a novel type of cutter blades mounted and actuated in a novel manner, the blade actuating means comprising a mandrel formed and adapted to be actuated by fluid under pressure into operative relation with the cutter blades whereby the latter may be actuated into cutting relation with the stuck pipe.

With the above and other objects in view this invention has particular relation to certain novel features of construction, operation and arrangement of parts an example of which is given in this specification and illustrated in the accompanying drawings, where-

in:

Figures 1 and 2 show the upper and lower ends of the cutter, respectively, partly in section.

Figure 3 shows a cross sectional view taken on the line 3—3 of Figure 1.

Figure 4 shows a cross sectional view taken on the line 4—4 of Figure 2, and Figure 5 shows a cross sectional view taken on the line 5—5 of Figure 2.

Referring now more particularly to the drawings, wherein like numerals of reference designate similar parts in each of the figures the numeral 1 designates the tubular cutter body whose lower end is rounded off, as at 2.

50 A cylinder 3 has its lower end threaded into

the upper end of said body, and there is a coupling 4 whose lower end is screwed into said cylinder by means of the intermeshing, coarse, threads 5. The lower end of this coupling carries a piston 6 which normally closes the outlet ports 7 of the cylinder 3. A tubular operating stem 8 is connected to the upper end of the collar 4 by means of which the tool may be operated from the ground surface.

The cutter body has a plurality of vertical grooves 9 therein and spaced apart there-around to receive the cutter blades 10. These blades are pivoted, intermediate their ends and work on the bearing pins 11 anchored to the head. Their upper ends have inwardly beveled faces, as 12, and their lower ends have the sharp cutting edges, as 13.

Within the body 1 there is a tubular mandrel 14 whose upper end is enlarged and thus formed into a piston 15 of slightly smaller diameter than that of the inside of the body for the passage of water downwardly through the body around the piston.

The upper end of the mandrel 14 carries a valve seat 16 controlled by the upwardly opening valve 17 which is confined by the cage 18, also carried by the upper end of said mandrel. The mandrel is supported by a coil spring 19 which surrounds the same and is interposed between the lower end of the piston 15 and the internal annular shoulder 20 carried by the body beneath said piston. Working in the upper ends of the grooves 9, and attached to said mandrel, there are the blade expanders 22 whose lower ends have the outwardly and downwardly flared faces, as 23, which work against the corresponding faces 12.

In operation the device is assembled as shown in Figures 1 and 2 and let down into the bore and it will be guided into the stuck pipe by the rounded off lower end 2 of the body. As lowered the fluid in the well will enter through the fluid passageway 24, of the body 1 and the mandrel 14, lifting the valve 17 and filling the stem 8. While being lowered the light springs as 25, will hold the cutter blades seated in their slots so that their lower ends will not swing out and engage the

walls of bore, or pipe. Fluid will then be pumped down through the stem 8 and will operate against the piston 15 and force the mandrel 14 and blade expanders 21 downwardly, overcoming pressure of the spring 19. The pressure fluid will pass on down around said piston and out through the ports 25' and the grooves 9. As the expanders 21 move downwardly their faces 23, operating against the opposing faces 12 of the respective blades 10 will force the upper ends of the cutter blades inwardly and their lower ends outwardly carrying the cutting edges 13 into contact with the pipe to be cut. The cutter is then rotated while the fluid pressure is maintained against said piston and the cutting edges are thereby held firmly against said pipe. Said cutters may be thus expanded until the upper ends of the blades seat against the opposing sloping faces 26 formed by inwardly widening the opposing parts of the grooves 9. While the cut is being made the pipe being cut may be placed under tension and when the cut is completed the severed 25 section will be moved upwardly suddenly, due to the elasticity of said pipe and the completion of the cut will thus be indicated to the operator. Under all conditions the cutter will rotate freely when the cut is completed, affording also indication to said operator. The pressure of fluid against the piston is then relieved and the spring 19 will then elevate the mandrel and blade expanders, relative to said body and the blades 10 will swing, by gravity, assisted by the springs 25, back into the grooves 9.

The upper end of the cylinder 3 has a notch 27 extending about three fourths of the distance therearound and a lug 28 is fixed to the coupling 4 and projects down into said notch. While the cut is being made, this lug works against the shoulder 29, at one end of said notch, and establishes a driving relation between said coupling and cylinder. Before withdrawing the tool the stem 8, and coupling 4 should be turned backwardly until the said lug 28 engages the shoulder 30, at the other end of said notch. The threads 5 have such a pitch that this backward turn of the coupling 4 will operate to elevate the plunger 6 above and clear of the ports 7. The cutter may now be withdrawn and the fluid in the stem will drain out through said ports 7 back into the bore as the cutter is withdrawn.

55 A preferred form of the invention has been shown and described, by way of illustration, but the broad principle of the invention will be defined by the appended claims.

What I claim is:

60 1. A pipe cutter including a body having a fluid passageway therethrough, cutters pivotally mounted in external longitudinal grooves in the body, a member having separate, detachable, blade expanders shaped to engage the upper ends of said cutters and

effective to thereby move the lower ends of said cutters outwardly, and fluid pressure operated means on said member.

2. A pipe cutter including a body, cutters pivoted to the body and having cutting edges at one end, a member above said cutters adapted to be moved downwardly and having separate means which move in independent bearings in the body and are shaped to engage the other ends of said cutters to move the cutting edges outwardly, a fluid pressure operated means on said member, a spring on said member above the cutters acting to hold said member normally raised.

3. A pipe cutter including a body having external longitudinal grooves, cutters pivoted in said grooves, a member above said cutters adapted to be moved downwardly and having separate, detachable expanders shaped to engage the upper ends of said cutters and effective to force the lower ends of the cutters outwardly, a fluid pressure operated means on said member, a yieldable seat supporting said member and normally holding said member elevated.

4. A pipe cutter including a body having external longitudinal grooves, cutters pivoted in said grooves, a member above said cutters adapted to be moved downwardly and having means which work in said grooves and are shaped to engage the upper ends of said cutters and effective to force the lower ends of the cutters outwardly, a fluid pressure operated means on said member, a yieldable seat supporting said member and normally holding said member elevated, there being a passageway through said body permitting the passage of fluid downwardly therethrough at all times during the operation of the cutter.

5. A pipe cutter including a body, cutters pivoted thereon, a member above said cutters adapted to be moved downwardly and having detachable expanders shaped to engage the upper ends of said cutters and move the lower ends thereof outwardly, a piston on said member, and a resilient means supported by the body and supporting said piston and normally holding said member raised.

6. A pipe cutter including a body, cutters pivoted thereon, a member above said cutters adapted to be moved downwardly and having separate detachable expanders shaped to engage the upper ends of said cutters and move the lower ends thereof outwardly, fluid pressure operated means on said member, said body and member having an inlet fluid passageway therethrough, and an upwardly opening valve controlling said passageway.

7. A pipe cutter including a body, cutters pivoted thereon, a tubular operating string to which said body is attached, said string having a drain port, a member above said cutters adapted to be moved downwardly and shaped to engage the upper ends of said

cutters and move the lower ends thereof outwardly, means operative by the rotation of the string to open or close said port, and a resilient means supported by the body and supporting said member.

8. A pipe cutter including a body, cutters pivoted thereon, a tubular member, including an operating string, to which the body is attached and which has a drain port, a member in said body adapted to be moved longitudinally of the body and shaped to engage the cutters at one end and move the other ends thereof outwardly, means rotatable by the string to open or close said port, fluid pressure operated means on said member within said body and spaced from the walls thereof to provide a passageway for fluid downwardly through said body about said fluid pressure operated means.
- 10 9. A pipe cutter including a body having external longitudinal grooves, cutters pivoted in said grooves, a member adapted to be moved longitudinally of the body and having means which work in alignment with said 15 grooves and are shaped to engage the cutters at one end and effective to force the other ends of the cutters outwardly, a fluid pressure operated means on said member, a yieldable seat against which said member works and 20 normally holding the member, and the cutter operating means carried thereby, in inactive position, there being a passageway through said body permitting the passage of a fluid 25 downwardly therethrough at all times during the operation of the cutter.
- 30

In testimony whereof I have signed my name to this specification.

WALTER L. CHURCH.
